(57) CLAIM

The ornamental design for a golf mat with a tee and imprinted lines for guiding foot placement, as shown and described.

DESCRIPTION

FIG. 1 is a perspective view of the golf mat with a tee and imprinted lines for guiding foot placement shown in full lines with a person illustrated in broken lines shown using the mat to drive a golf ball.

FIG. 2 is a top plan view of the golf mat with a tee and imprinted lines for guiding foot placement.

FIG. 3 is a bottom plan view thereof.

FIG. 4 is a front elevational view thereof, the rear view being a mirror image of the front view; and,

FIG. 5 is a right side elevational view thereof, the left side view being a mirror image of the right side view.
